R. J. WINSOR

ROAD WORKING MACHINE

Filed Nov. 14, 1924

Patented Jan. 5, 1926.

1,568,490

UNITED STATES PATENT OFFICE.

ROY J. WINSOR, OF BUCYRUS, OHIO.

ROAD-WORKING MACHINE.

Application filed November 14, 1924. Serial No. 749,860.

To all whom it may concern:

Be it known that I, Roy J. Winsor, a citizen of the United States, and a resident of Bucyrus, in the county of Crawford and

5 State of Ohio, have invented an Improvement in Road-Working Machines, of which the following description, in connection with the accompanying drawings, is a specification, like reference characters on the drawings representing like parts.

10 My present invention relates to road working machines, and more particularly to an improved road working machine whereby the operations of scarifying, scraping, and rolling the surface of a road may be performed in one operation and by a single unitary machine.

15 In road work it is at present customary and, because of the limitations in the apparatus, necessary to first run a machine over the road and scarify such road, the machine for scarifying being followed by a separate and distinct machine having a road scraping tool mounted thereon which scrapes and levels the surface of the road, and afterwards a third unitary machine is drawn over the road, which machine is supplied with a roller for rolling and compacting the surface of the road. With a view

20 to overcoming the objections above noted and for reducing the cost of upkeep of roads, I have designed a unitary machine wherein the scarifying, road scraping, and road working tools are mounted on, or are associated with, a single unitary power plant or propelling mechanism, the scarifier, road grading tool, and roller being mounted one behind the other and in the order named so that the necessary operations of scarifying, scraping, and rolling

25 take place in any point of a road successively and, considering the road as a whole, simultaneously. I preferably employ as a power or propelling mechanism my road grading

30 machine forming the subject matter of my copending application, Serial No. 630,498, filed April 7, 1923, and on such mechanism I mount in advance of the road working or grading tool thereon a scarifying tool such as described and claimed in my copending application, Serial No. 734,948, filed Aug. 29, 1924. Associated with such road working tool and adapted to be drawn thereby is an improved road roller which serves to compact the material of the road that has been scarified and scraped by the scarifier.

35 and road scraping tool respectively, it being considered that, after the roller has passed over the road, such road is complete and ready for use.

40 The principal object of my invention, therefore, is an improved, combined road scarifying, scraping, and rolling machine.

45 Another object of my invention is an improved and novel type of roller adapted for association with the road grading machine.

50 Other objects and novel features of the construction and arrangement of parts comprising my invention will appear as the description of the invention progresses.

55 In the accompanying drawings, illustrating a preferred embodiment of my invention,

Fig. 1 is a side elevation;

60 Fig. 2 is a plan view of the rear portion of Fig. 1 showing the method of attaching a road roller to the propelling mechanism;

65 Fig. 3 is a sectional elevation on the line 3—3 of Fig. 2;

70 Fig. 4 is a plan view similar to Fig. 2, but with the roller frame shown swung out of alignment with the rear of the propelling mechanism;

75 Fig. 5 is a fragmentary vertical sectional elevation on the line 5—5 of Fig. 1, and

80 Fig. 6 is an enlarged view of the left hand portion of Fig. 3.

85 Referring to the drawings, 10 designates, generally, a road grading machine or propelling mechanism comprised essentially of a unit power plant 11 having attached to its rear axle housing the rear ends of frame members 12 which extend forwardly and upwardly and thence downwardly, and the front ends thereof rest on, and are supported by, a front axle 13 provided with guiding wheels 14. The front end of the power plant 11 is supported on a bracket 15 extending between the side members 12, and immediately in front of the power plant 11 is a platform 16 on which the operator stands and also in front of the power plant on the frame members 12 is supported a seat 17 for the operator within convenient reach of control wheels 18 and steering wheel 19. Secured to the lower front end of the side frame members 12 in any suitable manner is a rearwardly extending sub-frame 20 to the under side of which is secured a circular track 21 on which is adjustably secured a frame 22 provided with a scraping tool 23. On the front of

the side frame members 12 is secured a member 24 to which are secured the ends of chains 25 attached at their rear ends to a scarifier tool 26 that is pivotally attached at 27 to the subframe 20.

Numeral 28 designates a rectangular frame, the side members of which are provided with yokes 29, the arms of which extend upwardly through perforations and such arms are threaded to receive the nuts 30. Such yokes are utilized to securely clamp in position on the under face of the rectangular frame 28 a shaft 31 on which is rotatably mounted a plurality of roller sections 32. These roller sections 32 are comprised of a cylindrical member provided with radially inwardly extending lugs 33 to which are secured the outer ends of rectangular spokes 34, the inner end of these spokes being secured to members 35 formed integral with, and extending outwardly from, a hub 36. The hub 36 is drilled to allow free rotation of the roller members 32 on the shaft 31 and the length of the hubs 36 is sufficient to prevent the outer periphery of the roller members from engaging with each other, as clearly shown in Fig. 5. The interior of the hub 36 is enlarged to form an annular chamber 37 which connects by means of an oil or grease cup 38 with the outer atmosphere and which grease or oil cup 38 is utilized to fill the annular chamber 37 with lubricant sufficient in quantity to obviate the necessity of frequent oilings of the shaft bearing.

Secured to the upper rear ends of each of the side frame members 12 in any suitable manner are pillow blocks 39 in which is rotatably mounted a shaft 40. Secured to the shaft 40 adjacent to each of the pillow blocks 39, but between such pillow blocks, are members 41 each provided with a rearwardly extending portion 42. The rear portions 42 are riveted to an angular iron member 43 that extends, as clearly shown in Figs. 2 and 4, transversely of the rear end of the unit power plant 11 and between the driving wheels of the machine. Secured to the upper central portion of the channel iron 43 and extending rearwardly therefrom to any convenient distance is a channel iron member 44. Secured to the ends of the angular iron member 43 are braces 45, the rearward ends of these braces being secured to the extreme rear end of the channel member 44. The channel member 44 is provided adjacent to its front end with a bearing plate 46. Secured to the front cross bar frame 28, as by riveting or in any other suitable manner and to the upper surface thereof is a substantially triangular plate 48. Secured to the under face of the plate 48 and extending forwardly therefrom to a point adjacent to the angular member 43 is a channel member 49. Secured to the for-

ward cross bar of the frame 28 adjacent to the ends of the triangular member 48 are braces 50, such braces extending forwardly and having their extreme forward ends secured to the front end of the channel member 49. Secured to the braces 50 adjacent to their rear ends is a bar 51 which lies parallel with the forward cross bar of the frame 28 and above the channel member 44. The forward end of the channel member 49 is provided with a bearing plate 52 in alignment with the bearing plate 46 on the channel member 44, and in these bearing plates is fitted a bearing pin 53. The rear end of the channel member 49 is provided with a perforation 47. Numeral 55 designates a pin mounted in the rear end of the member 44 and bearing plate 54, and this pin is adapted to enter perforation 47 to hold the roller frame 28 in alignment with the longitudinal axis of the machine 10. Secured to the upper surface of the channel member 44 adjacent to the rear end thereof is a member 56 to which is secured a bearing bracket 57. Pivotedly mounted in the bearing bracket 57 is a bell crank lever 58, one arm of which is pivotally attached to the upper end of the pin 55, while the other arm is pivotally attached to a reach rod 59 that extends forwardly toward the tractor unit 10, terminating adjacent to the operator's position thereon so as to be within convenient reach of the operator. The pin 55 above the channel member 44 is provided with a collar against which abuts a compression spring 60, the upper end of this spring engaging with the under face of the member 54, the spring 60 therefore constantly urging the pin 55 downward so as to engage in the perforation 47 when such perforation comes into alignment with the pin. If it is desired to allow a free movement of the roller frame 28 about the bearing pin 53, the pin 55 may be removed and the roller frame 28 therefore has a limited pivotal movement with respect to the longitudinal axis of the machine about the pivot bearing 53, as indicated in Fig. 4. The use of the pin 55 is useful when it is desired to back the machine 10 with the roller frame 28 attached.

Assuming the power plant 10 to have been furnished with the scarifier 26 at the front of the machine with the road scraping tool 23 immediately to the rear thereof and with the roller elements 32 at the rear of the entire structure, it is obvious that, when propelled along the road and properly manipulated, the road will be scarified and immediately after the scarified portion will be scraped by the blade 23, and finally the scraped portion will be rolled and put in final condition by the passage of the roller elements 32 thereover. I therefore am enabled by this apparatus to perform the

operations of scarifying, scraping, and rolling on any spot in a road consecutively while, considering a piece of road as a unit, I am enabled to perform the three operations of scarifying, scraping, and rolling simultaneously.

Having thus described my invention, what I claim as new is:

1. An improved roller for roads and the like, including, in combination, a rectangular framework, a roller mounted for rotative movement in said framework, a plurality of members pivotally attached to the front end of said framework, said members being adapted to be pivotally attached to a propelling mechanism, and means associated with the members and with the framework for preventing too great an angular
- 10
- 15

movement of the framework with respect to the propelling mechanism.

2. An improved roller for roads and the like, comprising, in combination, a rectangular framework, a roller rotatably mounted therein, a pair of members pivotally attached to the forward end of the framework and adapted for attachment to a propelling mechanism, said members crossing each other at an intermediate point, and means for securing said members together at their crossing point whereby relative movement of the members with respect to the rectangular framework, or each other, is prevented.
